UNITED STATES PATENT OFFICE.

FRANK F. WRIGHT AND HENRY M. KELL, OF AURORA, ILLINOIS.

DESIGN FOR A BRACKET FOR SHADE-ROLLERS AND CURTAIN-POLES.

40,481.

Specification for Design.

Patented Feb. 1, 1910.

Application filed October 16, 1909. Serial No. 523,090. Term of patent 14 years.

To all whom it may concern:

Be it known that we, FRANK F. WRIGHT and HENRY M. KELL, citizens of the United States, residing at Aurora, in the county of Kane and State of Illinois, have invented a new, original, and ornamental Design for Brackets for Shade-Rollers and Curtain-Poles, of which the following is a specification, reference being had to the accompanying drawing, forming part thereof.

Figures 1 and 2 are elevational views

showing respectively, opposite sides of our new design, and Fig. 3 is an edge elevation.

We claim:

The ornamental design for a bracket for a shade roller and curtain pole, as shown.

FRANK F. WRIGHT.
HENRY M. KELL.
